UNITED STATES PATENT OFFICE

144,123

DESIGN FOR A SERVICE PLAQUE

Milton B. Maxwell, Sr., Huntington Park, Calif.

Application September 18, 1945, Serial No. 122,165

Term of patent 3½ years

(Cl. D29—23)

To all whom it may concern:

Be it known that I, Milton B. Maxwell, Sr., a citizen of the United States, residing at Huntington Park, in the county of Los Angeles and State of California, have invented a new, original, and ornamental Design for a Service Plaque, of which the following is a specification, reference being had to the accompanying drawing, forming a part thereof.

I claim:

The ornamental design for a service plaque, as shown.

MILTON B. MAXWELL, SR.
